JOHN H. BURKHOLDER, OF ASHLAND, OHIO, ASSIGNOR, BY MESNE ASSIGNMENTS, TO
ELITE MANUFACTURING COMPANY, A CORPORATION OF OHIO

VEHICLE JACK

Application filed May 18, 1928. Serial No. 278,738.

This invention relates to an improvement in vehicle jacks, and more particularly to a jack of the double screw type in which one screw member telescopes within another and a follower device is provided to hold the inner screw member from turning while the outer screw is being rotated by gearing and a screw-threaded nut. In this particular type of jack when both screws are fully extended they are locked together and also locked to the nut so that should further cranking or rotative movement occur it is possible to disrupt or work injury to the follower or holding device. The object of 15 the present improvement in general is to provide a simple means for safeguarding the operation of the follower or holding device, so that no injury or breakage can occur thereto when the double lift screws are fully extended and joint rotation thereof is brought about by needless continued rotation of the gearing and cranking parts.

In the accompanying drawing, Fig. 1 is a sectional view of a double screw jack embodying my invention; Fig. 2 is a sectional view of the secondary screw, and Fig. 2a is a cross section thereof on line 2a—2a of Fig. 1. Fig. 3 is an enlarged side view and section of the follower and holding means, and 20 Fig. 4 a horizontal cross section, on the same scale as Fig. 3, but taken on line 4—4 of Fig. 1. Figs. 5 and 6 are side and sectional views corresponding to Figs. 3 and 4, but showing a modified form of the invention. Fig. 6 is taken on line 6—6 of Fig. 5. Figs. 7 and 25 8 are side and sectional views of a further modification, and Fig. 9 is a sectional view of still another form of the invention.

The jack comprises a hollow standard 2 having an arched top 3 which is provided with a round opening 4 axially of the standard and through which a pair of hollow telescopic lift members or screws 5 and 6, respectively, extend. A combined gear and nut 7 is rotatably supported upon ball bearing 8 within arched top 3, and a short shaft 9 extends through a bearing 10 at one side of top 3, which shaft carries a pinion 11 to rotate gear nut 7. Any suitable means such as a rotatable handle or crank (not shown) 50 may be connected with shaft 9 to crank or rotate it, as commonly practiced. Nut 7 is screw-threaded internally to engage with the threads on screw 5, which extends downwardly into standard 2 in sliding engagement with the wall thereof. The upper end of outer screw 5 is screw-threaded internally to engage the screw-threads on the inner screw 6, which is surmounted by a serrated cap or rest member 14 adapted to engage or support the load. Inner screw 6 is tubular and provided at its bottom with a square opening to receive a square shaft or follower rod 15 which may be upset or expanded at its top to effect uplift of this member when lift screw 6 moves upwardly a predetermined distance. The lower end of follower shaft 15 is provided with a holding device 16 which is constantly held in slidable contact or engagement with hollow standard 2. As shown in Figs. 1 to 4, standard 2 is formed with a pair of longitudinal grooves or channels 17—17 into which the opposite ends or reduced extensions 18—18 of holding device 16 project.

This device is in the form of a flat metal disk or plate 16 having a round central opening 18 through which the square rod or shaft 15 extends. A round flat disk 19 is riveted or otherwise affixed to the bottom end of rod 15, and a split spring ring or washer 20 interposed between the plate 16 and disk 19. A cotter pin 21 or other fastening device on the rod or shaft holds the plate, split ring and disk in tight frictional engagement, so that considerable force is required to turn the rod or shaft independently of the plate or holding device 16. A coiled compression spring may be used in lieu of spring washer 20, but the latter is preferred as a more com-

pact assembly of parts can be obtained and the height of the standard reduced accordingly.

When the lift screws are telescoped with 5 in each other and the standard the follower device 16 is at rest upon the bottom piece 22 within the standard.

Uplift of the inner screw 6 is produced by 10 rotating the gear and nut, the outer screw 5 rotating with the nut because the friction between this screw and nut is greater than the friction between the two screws 5 and 6, regardless of whether the screws are idling or carrying a load. The inner screw 6 is 15 prevented from rotating by the holding device 16. Now assume a load is being raised and that the cap at the top of inner screw 6 is engaged with the load. Screw 6 is first to move upwardly (without rotation) and its 20 upward travel within the outer screw 5 is limited or fixed by a pin or stop element 23 at the bottom or end of the screw thread.

Thus as soon as stop pin 23 reaches the 25 screw-threaded area in the upper part of the outer screw the two screws are locked together and further rotation of the gears in the same direction will cause the nut to drive the outer screw upwardly. The holding device 16 prevents inner screw 6 from turning 30 and when the two screws are locked together it follows that the outer screw is also prevented from turning by the same device. Accordingly as rotation of the gearing continues the outer screw is raised, carrying the 35 inner screw with it, until the limit of upward travel of the outer screw is reached relatively to nut 7. This limit of travel is established by a pin 24 or other device carried by screw 5 at or near the lower end of its screw-thread. Thus when pin 24 comes into contact with the bottom of nut 7 the outer screw 40 5 and the nut are locked together. Consequently a continued rotation of the gearing would then not only cause the nut to rotate 45 but it would also cause the outer screw to turn with the nut. Inasmuch as the inner screw is locked to the outer screw when fully extended the force applied to rotate the nut and screws would then be transmitted to the 50 square follower shaft or rod and thence to the holding device 16. Now assume the operator is not aware of the critical position of the working parts, and continues to apply power to the jack mechanism.

55 The next thing that happens, is that the rod or shaft becomes either badly bent or twisted, or the follower device 16 loosens or breaks, providing the rod or shaft, or the holding device, is not constructed to yield or surrender to such excessive strains.

60 The function of the present holder 16 is to grip the rod frictionally or with yielding tension to prevent turning or rotation of the inner screw under normal operating conditions, but when the screws are fully extended

and interlocked with each other and the nut, the holder 16 yields and relieves the turning stresses or torsion on the follower shaft and holding device, thereby safeguarding operations and preventing injury or breakage.

70

The means for holding the inner or secondary screw yieldingly against rotation may be located at either end of the follower rod or shaft, but in Fig. 1, it is shown at the bottom of the shaft and engaged with the walls of the hollow standard or supporting column.

75

In Figs. 5 and 6, a modified form of holding device is shown, comprising a dished or flanged plate 25 carrying a pair of bowed wire springs 25' which engage the flat sides of the follower rod or shaft. Normally the shaft and plate are locked together, but under severe torsional stress the square rod or shaft will turn with a snap movement between the pair of wire springs.

80

In Figs. 7 and 8, a pair of spring pressed balls or plungers 26 are mounted within the opposite ends of a plate or cross bar 27 fixed to the rod or shaft. The balls or plungers project into rounded channels or grooves 28 in the side walls of the standard and the rod or shaft is prevented from turning under normal operating conditions in the jack but surrenders under the more severe stresses when the screws are completely extended and 95 interlocked.

90

In Fig. 9 the square follower rod or shaft 15 is provided with an S-shaped wire spring 29, the curved spring portions of which bear frictionally against the circular inner wall of the hollow standard, or within the hollow screw, as may be elected, to prevent injury or breakage to the working parts when the screws are fully extended, and a rotative movement is imparted thereto.

100

What I claim, is:

1. A vehicle jack, comprising a hollow standard having guideways; a pair of lift screws and a rotatable nut mounted upon said standard; means for rotating said nut to elevate said screws; means for interlocking said screws and the nut when the screws are fully extended; a follower element connected with one of said screws; and a holding device engaging said guideways, having frictional rotatable connection with said follower element.

110

2. A vehicle jack, comprising a hollow standard; a rotatable nut mounted upon said standard a pair of telescopic screws mounted upon said standard and cooperating with said nut; means for rotating said nut; a shaft connected to slide within and rotate with one screw; a holding device rotatably connected to said shaft and slidably interlocked with the wall of said standard; and a friction washer attached to said shaft in frictional contact with said holding device.

120

3. A vehicle jack, comprising a standard having guideways, a pair of cooperating tele-

130

scoping screws within said standard adapted to interlock when extended; means including a rotatable nut mounted upon said standard adapted to rise and lower said screws, a follower member slidably connected with one screw, a rotatable member pivotally connected with said follower member and slidably engaged with the guideways of said standard, and frictional means between said follower member and said rotatable member permitting rotation of said follower member and the screws when both screws are fully extended beyond the standard.

In testimony whereof I affix my signature.
